[57] CLAIM

The ornamental design for a toy playhouse, as shown and described.

DESCRIPTION

FIG. 1 is a side elevational view of a toy playhouse showing my new design, the side opposite being a mirror image;

FIG. 2 is a cross-sectional view of the design of FIG. 1 taken along line 2—2 in FIG. 1;

FIG. 3 is a front elevational view thereof;

FIG. 4 is a rear elevational view thereof;

FIG. 5 is a top plan view thereof; and

FIG. 6 is a bottom plan view thereof.

FIG 2

FIG 1

FIG 3
